UNITED STATES PATENT OFFICE.

JULIUS KAHN, OF YOUNGSTOWN, OHIO, ASSIGNOR TO TRUSSSED CONCRETE STEEL COMPANY, OF DETROIT, MICHIGAN, A CORPORATION OF MICHIGAN.

WINDOW-FRAME.

1,292,795.

Specification of Letters Patent. Patented Jan. 28, 1919.

Application filed November 2, 1917. Serial No. 189,829.

To all whom it may concern:

Be it known that I, JULIUS KAHN, a citizen of the United States, and residing at Youngstown, in the county of Mahoning and State of Ohio, have invented a new and Improved Window-Frame, of which the following is a specification.

This invention relates to metallic frameworks adapted for window sashes, and particularly to the joints between the longitudinal and transverse bars which constitute such sashes, and its object is to provide a joint between the bars of a structure of this character which will have a high degree of strength and rigidity, which shall secure the intersecting members against displacement, and which shall be simple in construction, easy to assemble and economical to manufacture.

These and other objects of my invention are attained by the particular formation and arrangement of parts of the intersecting bars or members which are pointed out in the claim.

In the accompanying drawing Figure 1 is a perspective of two intersecting bars connected by my improved joint. Figs. 2 and 3 are perspectives of the two bars. Fig. 4 is a section on the line 4—4 of Fig. 1. Fig. 5 is a perspective showing a slightly modified joint.

Similar reference characters refer to like parts throughout the several views.

The two intersecting bars are formed with webs 1 and 2 and with flanges 3 and 4 respectively. If desired, the outer edges of the webs may be slightly heavier than the remainder of the web. One of the bars is formed with a main cross notch 5 extending through the flanges 4 and into the web 2, and with two other notches 6 parallel to the notch 5 but extending through the flanges 4 alone. The distance between the outside walls of the notches 6 is preferably the width 45 of the flanges 3 of the other bar. The

tongues 7 thus formed by the notches 5 and 6 may be of any desired length.

The second bar is formed with a notch 8 in the edge of its web 1 and with two holes 9 in the flanges 3 of proper size to receive 50 the tongues 7 of the first bar. When the bars are assembled, as shown in Fig. 1, they may be secured together by electric welding, if desired.

The metal of the flanges 3 extends around 55 the tongues 7 and constitutes a link or bridge across the main cross notch from one tongue 7 to the other and this bridge transmits tension from one portion of the flanges 4 to the other across this gap. The tension member at this side of the web 2 is therefore again complete.

The result is a strong sash construction that can be easily and quickly assembled and which may be made permanent by welding the adjacent edges of the flanges 3 and 4 together. The tongues 7 may be left full length, as in Fig. 5, or may be shortened as shown in Figs. 1 and 3. The other proportions and details may all be varied as desired without departing from the spirit of 70 my invention as set forth in the following claim.

I claim:—

In a metal window sash, a pair of intersecting T shaped bars, each consisting of a web and two flanges, one of the bars being formed with a main cross notch extending through the flanges and through a portion of the web and with a lateral notch parallel 75 to and on each side of the main notch and extending through the flanges so as to leave a pair of tongues separated by the main cross notch, the second bar having holes 80 through its flanges to receive said tongues when the second bar is fitted into the notch in the first, the edge of the web of the second bar being notched to receive the remaining portion of the web of the first bar.

JULIUS KAHN.
